UNITED STATES PATENT OFFICE.

OTTMAR MERGENTHALER, OF BALTIMORE, MARYLAND, ASSIGNOR, BY MESNE ASSIGNMENTS, TO THE MERGENTHALER LINOTYPE COMPANY, OF NEW YORK, N. Y.

LINOTYPE-MACHINE.

SPECIFICATION forming part of Letters Patent No. 678,268, dated July 9, 1901.

Application filed May 17, 1898. Serial No. 680,964. (No model.)

To all whom it may concern:

Be it known that I, OTTMAR MERGENTHALER, a citizen of the United States, residing at Baltimore, in the State of Maryland, have 5 invented certain new and useful Improvements in Linotype-Machines, of which the following is a specification.

My invention relates to what are known in the art as linotype-machines designed to produce printing-forms composed of linotypes—that is to say, line-bars—each bearing on its face, properly justified, the characters to print an entire line.

It relates more particularly to that class of 15 machines originated by myself in which a series of disconnected matrices representing individual characters are through the instrumentality of escapement mechanism controlled by finger-keys delivered from a magazine, composed or assembled in line, justified, and presented to the face of the mold, which is then filled with molten type-metal to produce the required bar or linotype, having on its face an impression of the assembled matrices. After these operations the 20 matrices are returned through a distributing mechanism to the magazine from which they started.

The present machine is of the same general 30 character as those represented in numerous Letters Patent heretofore granted to me—such, for example, as Letters Patent No. 317,828, dated May 12, 1885, and No. 378,798, dated February 28, 1888, but more particularly to that form of machine represented in 35 the Letters Patent granted to me, Nos. 436,531 and 436,532, dated September 16, 1890.

The present invention is designed to simplify and to reduce the cost of manufacture 40 of the machine; and to this end it consists in various improvements in construction and operation, which are hereinafter to be described in the specification and finally pointed out in the claims.

45 Referring now to the drawings, Figure 1 is a front view of my improved linotype-machine, showing such parts of the machine as are at the front thereof. The portions of the machine at the back have been omitted from 50 this view in order to avoid confusion in the

figure. Fig. 2 is a front view, on an enlarged scale, of certain portions of the assembling devices and the parts connected therewith. Fig. 3 is a vertical sectional view of the mold, justification-plate, and the devices for locking the sliding jaw and shows also a portion of the stopping and starting devices. Fig. 4 is a front view, partly broken away, showing the distributing-box, the distributor-shifter, and a portion of the distributing mechanism 60 proper. Fig. 5 is a vertical sectional view of the assembling mechanism and of the keyboard substantially on the line 5 5 of Fig. 2. Fig. 6 is a vertical sectional view of the assembling-box, showing also the yielding 65 resistant and the retaining-pawl, which also determines the length of the line, taken substantially on the line 6 6 of Fig. 2. Fig. 7 is a rear view of the plate which carries the gearing from the lower roller of the assembling-belt 70 for actuating the assembling-star. Fig. 8 is a detail sectional view of the assembling-plate, showing the mode of attachment of the partition-plates to the rear plate, taken substantially on the line 8 8 of Fig. 5. Fig. 75 9 is a diagrammatic front view of the mold, slug-shifter, and the two trimming-knives for shaving the front edges of the slug or bar. Fig. 10 is a view of the knife-box and pressure devices which are used in connection with the second edge-trimming knife. Fig. 11 is a view, partly broken away and partly in section, on the line 11 11 of Fig. 10, showing the knife-box and the slug-shifter. Fig. 12 is an end view of the knife-box, showing also the mold, the slug therein, the first 80 edge-trimming knife, and the ejector-blade, partially in section. Fig. 13 is a sectional view of the pressure devices and knife-box, taken substantially on the line 13 13 of Fig. 90 10. Fig. 14 is a horizontal sectional view viewed from above of my improved linotype-machine, illustrating clearly the positions of the cams, cam-levers, and other operating devices which are located in the lower part of the machine. Fig. 15 is a vertical sectional view, also partly broken away, showing the pot, pump, mold, and elevator and the actuating devices therefor. Fig. 16 is a similar 95 view showing the justifying mechanism and 100

jaw-locking device and the actuating mechanisms therefor. Fig. 17 is a similar view, but in detail, showing the justification-lever raised and in the position which permits the 5 jaw to be locked. Fig. 18 is a vertical sectional view showing in part the automatic starting arrangement for the main cam-shaft when the elevator is first lowered and also showing a portion of the elevator-actuating 10 devices. Fig. 19 is a diagrammatic view of the automatic and hand-operated starting and stopping devices, but taken at right angles to the view shown in Fig. 18. Fig. 20 is a detached side view showing the mold, 15 ejector, and the knife for trimming the base of the slug, together with the actuating devices therefor. Fig. 21 is a similar view taken from the other side and showing particularly the devices for imparting an intermittent 20 rotation to the mold and the stop devices for firmly holding the mold in its adjusted positions. Fig. 22 is a view of my improved machine, taken from the left hand thereof and partly in section. Fig. 23 is a detached front 25 view of the elevator, partly broken away in order to show the retaining-pawl employed to confine the line of matrices longitudinally therein. Fig. 24 is a top view of the elevator and parts shown in Fig. 23, partly broken 30 away to show the channels therein which are employed to receive and retain the shoulders of the matrices and space-bands. Fig. 25 is a partial side view of my improved machine, taken from the right-hand side thereof. Fig. 35 35 26 is a detail view showing in vertical section the construction of the space-band box. Fig. 27 is a diagrammatic detail view of a portion of the space-band box, showing, on an enlarged scale, the operation of the release of 40 the space-bands therefrom. Fig. 28 is a similar diagrammatic view, on an enlarged scale, of a portion of the space-band box, but showing the escapement-pawl in retracted position. Fig. 29 is a detail view taken in vertical section 45 substantially on the line 29 29 of Fig. 30, showing the construction of the distributor mechanism and of the upper part of the magazine. Fig. 30 is a detail view, partly broken away, of a portion of the distributing mechanism and of 50 the automatic stop devices therefor. Fig. 31 is a similar detail view showing in section, substantially on the broken line 31 31 in Fig. 29, the connection between the upper part of the magazine and the automatic stepping device for the distributing mechanism. Fig. 32 55 is a sectional view taken substantially on the line 32 32 in Fig. 4 of the upper portion of the channel leading to the space-band magazine from the distributor-box, showing in detail the method employed for separating the space-bands from the matrices. Fig. 33 is a view showing the form of matrix employed in this machine. Fig. 34 is a sectional view, taken substantially on the line 34 34 in Fig. 60 30, showing the gearing for actuating the distributor-screws.

My improved machine is intended to han-

dle matrices such as are shown in Fig. 33 in connection with the space bars or wedges such as are shown in Fig. 32. The matrices 70 Y, properly assorted, are contained in the elevated magazine B, having a series of channels through which the matrices descend to the escapement devices at the bottom thereof which are actuated through the escapement- 75 rods E, operated in turn by the finger-keys D. Similarly the space-bands Z are contained in the space-band box K and are released therefrom by an escapement device hereinafter to be described, operated from a suitable finger- 80 key. The discharged matrices, which are released in the desired order and one at a time, descend through the guiding-channels G, formed in the assembling-plate, and are received on the upper surface of the traveling 85 belt H, by which they are delivered successively into and assembled in line in the slotted assembling-box I. The space-bars Z are released one at a time when desired in such manner that they descend into the assembling-box 90 to be added to the line of matrices. As the line of matrices and space-bars is assembled it is held in compact form by the yielding resistant J, which is moved to the left step by step as the matrices and space-bars are delivered into the assembling-box by means of the 95 rotating assembling star or cam H¹³. When the line is completed, the operator shifts the line manually to the left through the guide M until it is introduced and contained within 100 the elevator N. The elevator N is then manually released by the operator and descends by its own weight until the line of matrices and space-bars is brought into proper position in front of the mold. This descent of the elevator through mechanism hereinafter to be 105 described automatically starts the further operation of the machine which effects the proper movements of the pot S and mold O' and the justification of the line through the justifying-piece Q, the proper locking and clamping of the line longitudinally through the sliding jaw R, and the ejection by means of the pump-plunger S⁸ of the molten metal from the pot S into 110 the mold and against the faces of the matrices 115 in front thereof. The parts are then released from their casting positions and the mold turned through an angle of two hundred and seventy degrees in such manner that the base of the slug is trimmed by reason of its passage 120 against and by a stationary knife S²¹. When the mold comes to rest again, the ejector starts forward through the mold and forces the linotype out of the mold a distance of about an eighth of an inch, when the knife S²² starts to 125 descend and trims one of the front edges of the slug or linotype throughout its entire length. After this trimming of one edge of the linotype or slug the ejector acts further to force the linotype or slug completely from 130 the mold and into the knife-box S³¹, which contains the knife for trimming the other edge of the slug or linotype. In this position the slug is engaged and forced longitudinally by

means of a slug-shifter S^{32} through the knife-box and passes the knife contained therein, which trims the other front edge of the linotype or slug throughout its entire length.

5 The linotype or slug is then dropped into position to be engaged by a vibrating finger S^{49} , which assembles it with the linotypes previously cast in a chase or form S^{48} in suitable order to be printed from. During this 10 operation of the ejection and trimming of the slug the elevator N has ascended to the upper portion of the machine, carrying with it the line of matrices and space-bars until they register exactly with the distributing-box.

15 The line-shifter W then moves in to the right, carrying the line of matrices and space-bars into the distributing-box, where the space-bars are separated from the matrices by means hereinafter to be described and returned to the 20 space-band box or magazine. The shifter W continues to move the line of matrices toward the distributing mechanism X , where they are engaged one by one and returned to their proper channels in the magazine. In the 25 meantime the elevator N has descended to its original position in a state of rest and the operation of the cam-shaft and parts connected therewith has been stopped automatically by means hereinafter to be described. It will be 30 seen that, as in my previous patents referred to, the matrices and space-bands are returned to their proper magazines by a path different from that which they pursued during the course of assemblage, or, in other words, that 35 I still employ herein what is termed in the art as the "circulating system." This feature enables the operator to start in upon the composition of a second line immediately after he has transferred the first line to the elevator 40 and releases the elevator, so that it may descend to its operative position, as the further operations of justifying, casting, ejecting, trimming, and distributing are entirely automatic.

45 *Matrices.*—The matrices employed in the machine are preferably identical in construction with those described in my Letters Patent Nos. 436,531 and 436,532, previously referred to. As shown in Fig. 33, each matrix 50 Y consists of a flat rectangular plate of brass, steel, or like material provided in one edge with the intaglio letter or matrix proper and recessed in its two vertical edges to produce the four shoulders Y' . The matrix is also 55 notched centrally in its upper edge and provided with sustaining-teeth Y^2 , the number and arrangement of which differ on matrices bearing different characters, so that they may be employed as a means of distinguishing between 60 and distributing the matrices in the manner set out at length in Letters Patent No. 347,629, granted to me on the 17th day of August, 1886, as well as in numerous other Letters Patent granted to me.

65 *Space-bars.*—The space-bars or justifying devices are of the same character as those described in numerous Letters Patent here-

tofore granted to me—such, for example, as the Letters Patent previously referred to, Nos. 436,531 and 436,532. As shown in Fig. 32, each bar consists of a long wedge Z, carrying on one side a second and shorter wedge Z', which is provided at the upper end with sustaining-shoulders Z² and which is tapered in the opposite direction and connected to the long wedge Z by a dovetail or other sliding joint. 70 75

Main frame.—The main frame A may be of any suitable form to sustain the working parts of the machine, provided only it affords a rigid support for the various operative parts hereinafter described. I have shown, however, and preferably employ herein its construction with a vertical post or pillar A', on which the keyboard mechanism, the assembling mechanism, the matrix-magazine, and the distributing mechanism may be firmly placed and secured. This is or may be effected by the employment of collars A² A², which may be slipped over the post or column A' and secured thereto in the desired position by means of set-screws A³ A³. This form of construction and arrangement affords me a simple and perfectly practicable method of adjustment and attachment, insuring the independent and exact adjustment of the parts in their desired positions.

The matrix-magazine.—In the present form of machine the matrix receptacle or magazine B is employed in vertical position instead of in inclined position, as in the Letters Patent Nos. 436,531 and 436,532, previously referred to. This magazine B consists, essentially, of a front plate B² and a rear plate B', one overlying the other and divided between their approximate faces into a large number of longitudinal grooves or receptacles for the matrices by means of the intermediate partitions B⁸. (See Fig. 29.) It will be observed that under this arrangement the matrices are held end to end in rows or lines in their respective compartments and permitted to slide freely downward between the plates, those in one line being kept out of contact with the adjacent lines.

The construction of the magazine-channels may be similar to that illustrated and shown in my Letters Patent No. 436,532, it being noted that the magazine as a whole is flared or made in fan shape, the upper ends of the magazine-channels being separated, so as to facilitate the proper distribution of the matrices. From the upper part of the magazine to the lower part the channels gradually converge, so that at the lower extremities the series of channels lie closely together and in close proximity to the receiving-channels G. This convergence of the channels may be secured by tapering the intermediate partition-plates B^8 or in any other suitable manner.

At the lower part of the magazine the front plate B² is provided with doors or inlets B³, hinged upon the transverse rod B⁵ and ordinarily retained in closed position by means

of the pivoted springs B⁴. (See Fig. 2.) By turning the several springs B⁴ about their pivots the doors or inlets B³ may be opened, so as to permit access to the magazine-channels. It will be noticed that the location of the doors B³ at the bottom of the plate B² gives a ready and convenient access to the magazine-channels at the front of the machine and in close proximity to the operator.

10 The rear plate B' is provided with lugs B⁷, Fig. 29, which are adapted to pass over and engage the horizontal rod B⁶, attached to the main frame of the machine and which sustains the magazine in pendent position, so that it may abut at its lower end against a suitable portion of the frame of the machine and remain in proper adjustment with the assembling-plate hereinafter to be described. It will be seen that all that is necessary to secure a change of font is to lift the magazine from its position by disengaging the lugs B⁷ from the rod B⁶ and to substitute therefor another and similar magazine containing the desired characters.

25 The upper portion or mouth of the magazine which receives the matrices from the distributing mechanism is constructed in the following manner: Pivoted at B⁴⁶ to the plate B² of the magazine are the two upright plates B¹⁰ B¹⁰, slotted vertically, as clearly shown in Figs. 29, 30, and 31, to receive the reduced ends of the partition-plates B⁹. These ends of the partition-plates B⁹ pass through the vertical slots in the upright plates B¹⁰ B¹⁰ and are secured therein by means of a rod B¹¹, which passes between the two uprights B¹⁰ B¹⁰ and through corresponding holes formed in the reduced ends of the partition-plates. This method of adjustment is one of great simplicity and permits of the ready change of a partition-plate simply by the withdrawal of the rod B¹¹. These partition-plates B⁹ are held against vertical displacement by the longitudinal bearing-bar B¹⁴ under which they lie. The portion B¹² of the partition-plate which is in direct proximity with the mouth of the magazine proper is made corrugated in form, as clearly shown in Figs. 29, 30, and 31. This corrugation is made use of to adjust just the passages to the exact width of the matrix, so as to prevent their turning, as the upper ends of the channels of the magazine B, as before stated, are made much wider than is necessary to hold and retain the matrix. The other end of the partition-plate B⁹ rests on and within the kerfs of a serrated longitudinal plate B¹³, which is also attached to the upper plate of the magazine. These kerfs or serrations in the plate B¹³ permit a certain amount of resilient lateral movement to the partition-plates B⁹, which is availed of to stop the distributing mechanism when a matrix is misplaced in the manner hereinafter to be described. It will be seen that the pivoting of the magazine-mouths at B⁴⁶ to the magazine proper permits them to be swung out and gives a ready access thereto.

The magazine as a whole is light and simple in construction and dispenses with the heavy and cumbrous metal castings sometimes employed in machines of this class.

Matrix-delivering mechanism.—At the lower end of the magazine I provide each channel with an escapement which allows the discharge of a single matrix at a time. 75 This escapement (which is clearly shown in Fig. 5) is practically identical with that shown and described in my Letters Patent Nos. 436,531 and 436,532, previously referred to. It consists of a centrally-pivoted lever or 8c plate E², pivoted to the magazine and provided at its opposite ends with the horizontal pins E⁴ E⁴, which play alternately into the magazine, so that when the lower pin E⁴ is retracted to release the lowermost matrix in 85 the line the upper pin E⁴ will advance into the channel to arrest the downward movement of the next matrix. A spring E³ acts constantly on the rear end of the escapement-lever E² and assists the inward movement of the upper pin E⁴ when the latter is permitted to act through the operation of the mechanism now to be described. The rear portion of the escapement lever or plate E² is formed with a notch, which engages a similar notch 95 in the upper end of the escapement-rod E. These escapement-rods E are located at the rear of the assembling-plate and are suitably guided at their upper portions in a rack or recessed plate C², attached to the assembler-plate, hereinafter to be described. At their lower ends these bars E pass into a rack or guide D³, attached to the keyboard, and rest therein upon the bars or plates D², which in turn are actuated by the finger-keys D, pivoted at D'. Springs E' E' are attached to the guide or rack D³ and to the escapement-rods E in such manner as to hold the escapement-rods in a depressed position and are of such strength as to overcome the tendency of the 105 springs E³ to turn the escapement plates or levers E² and to withdraw the lower pins E⁴ from the magazine-channels. When, however, the finger-key D is operated, the escapement-rod E is raised against the pressure of 110 the springs E', and the spring E³ is thus permitted to operate the escapement-lever E² and withdraw the lower pin E⁴ in such manner as to permit the release of a single matrix in the manner well known and understood in 115 the art. When the finger-key D is released, the spring E' restores the escapement-rod E to its original position and overcomes the pressure of the spring E³, thereby withdrawing the upper pin E⁴ and reinserting the lower 125 pin E⁴ in the magazine-channel, when the next matrix is in position to be released in the same manner. It will be understood that the escapement-rod E may be directly connected to the finger-key D and the plate D² dispensed 130 with, if desired.

It will be observed that in the present machine I dispense entirely with the automatic delivery and escapement devices, as illus-

trated in my Letters Patent Nos. 436,531 and 436,532, previously referred to, and that I substitute therefor the simple and directly-acting escapement mechanism above described.

Assembling mechanism.—The assembling and transferring mechanism of the present machine are of the same general character as those described and claimed in my Letters Patent Nos. 436,531 and 436,532, previously referred to, but differ therefrom in various minor features and will be hereinafter pointed out. On being discharged from the magazine the matrices descend vertically to the vertical channels or guides formed within the entrance-plate. These channels or guides G are formed between the plates G⁴ G⁴ by partition-plates G³, which are attached to the rear plate G⁴ in the manner clearly shown in Figs. 5 and 8. Each partition-plate G³ is provided with two or more projecting lugs, which pass through corresponding recesses in the rear plate G⁴ and are there retained by means of the rods G⁵, which pass through holes in the lugs of the partition-plates G³, firmly retaining them in position. This form of construction affords a simple and easy means of substituting or changing the partition-plates G³. The front plate G⁴ at its lower edge is hinged at G¹⁰ in the manner clearly indicated in Figs. 1 and 2, so as to permit access to the guides or channels G. The lower ends of the ribs or partitions G³ are deflected slightly to the left, as in the former patents referred to, and terminate near the inclined belt H, in order that the matrices may be presented flat-wise and with proper end foremost upon the belt. The upper ends of the escapement-rods E, as before stated, are contained within and guided by the rack or guide G². This rack G² is attached to the piece or bar G', which is connected to the back plate G⁴, Figs. 2 and 5. Attached to the bar G' is the spring G⁷, which is also connected to the frame of the machine, Fig. 14. The piece G' is provided with elongated screw-holes, through which the supporting-screws G⁶ pass into the frame of the machine, Fig. 2. It will be seen that the tendency of the spring G⁷ will be to force the entrance-plates and channels G constantly to the left, sliding them upon the screws G⁶ until the piece G' abuts against the adjusting-screw G⁸. (See Fig. 2.) In this manner I am enabled to secure an exact and constant registration between the assembling-channels and the mouths of the magazine and also through the attached rack or guide G² of the escapement-rods E and the escapement-levers E². The belt H is carried around the pulleys H', H⁷, and H⁸. Instead of employing the bevel and other gearing of my prior patents motion is directly imparted to the upper pulley H' from the pulley H⁶ on the intermediate power-shaft H²⁵ through the medium of belt H⁵ and pulley H⁴, which is fast on the rear end of shaft H³. (See Figs. 2, 14, and

25.) The pulley H' is attached to and turns with the shaft H³ by means of the hand-clutch H², which is within easy reach of the operator and whereby he is enabled to stop or start the belt H at will, Figs. 2 and 25. It will be noticed that at the lower end of the belt H instead of one pulley I employ two pulleys H⁷ and H⁸. These two pulleys are so located as to give the belt an angular turn at its lower end and to insure the delivery of the matrix in an approximately vertical position, thereby enabling me to dispense with the plate, which is shown as straddling the lower end of the belt in my Letters Patent No. 436,532.

At the lower end of the assembling-belt H and directly in front of the assembling-box is the assembling star or cam H¹³, which serves to force the descending matrices forward one after another into the assembling-block, where they stand in vertical position side by side, as shown in Fig. 2. A guide-piece H¹⁴, above the assembling-star H¹³ and near the lower end of the assembling-belt H, serves the double purpose of checking the space-bands in their fall and of preventing the matrices from falling off the belt H and insures their proper delivery in front of the assembling-star H¹³. Motion is imparted to the assembling-star H¹³ from the belt-pulley H⁸ in the manner shown in Figs. 5 and 7. The journal of the pulley H⁸ is continued rearwardly through the supporting-plate H²⁶ and carries fast on its end the pinion H⁹, which gears into a pinion H¹⁰, also journaled in the said plate H²⁶. This pinion H¹⁰ gears in turn into a third pinion H¹¹, loose on the shaft, which carries the assembling-star H¹³, but which ordinarily causes the rotation of the said shaft and star by reason of the spring connection H¹², fast on said shaft. This spring connection H¹², however, permits the stoppage of the assembling-star H¹³ in case a matrix or space-band should become jammed or wedged in front of it, and thereby prevents the breakage of the parts. In front of the assembling-star H¹³ and of the pulleys H⁷ and H⁸ a glass plate H¹⁵ is provided, which is held in a frame H¹⁷, (see Figs. 2 and 5,) pivoted at H¹⁸ in such manner that the plate H¹⁵ may be swung to the right, so as to permit access to the parts within. The spring H¹⁶ holds the plate firmly when it is closed, and a set-screw H¹⁹ limits its inward motion.

The space bands or bars are suspended in their magazine K, are delivered one at a time therefrom, and descend through the channel or conductor K' to the front of the assembling-block, into which they are carried in the same manner as the matrices and added to the line in the course of composition or assemblage. The space-bar magazine K is substantially similar to the space-bar magazine illustrated in my former Letters Patent Nos. 436,531 and 436,532, previously referred to. It is provided, however, with a pivoted cover K¹⁰, which is formed with a centrally-depending

lug or bar K²⁵, which is so shaped as to project between the lugs or ears Z² of the space-bars. This cover when closed rests upon the stop K¹¹ and holds the space-bars securely in 5 the magazine, but does not prevent the liberation of the space-bars one by one by the escapement mechanism hereinafter to be described. (See more particularly Figs. 1, 26, 27, and 28.)

10 The release of the space-bars one at a time is effected from the space-bar key K², (see Fig. 5,) pivoted at K³ and acting upon the escapement-rod K⁴, which acts in turn upon the end of the pivoted lever K⁵, (see Fig. 2,) which is 15 pivoted to the escapement-lever proper, K⁶, pivoted at the base of the magazine K. At the end of the escapement-lever K⁶ are pivoted the escapement-pawls K⁷, which are normally held inward against the magazine by 20 the springs K⁸ in such manner that the pawls K⁷ will engage one, and only one, of the space-bars in the magazine. Fast to the lower end of the magazine K is the projecting piece K⁹, which rests in contact with the outer or extreme space-bar and holds the series from 25 further downward movement until the outer one is released by the action of the escapement-pawls. When the finger-key K² is depressed through the connections already described, the pawls K⁷ are elevated and engage under the shoulders Z² of the outermost space-bar Z and lift it until it is free from the piece K⁹ and until its upper shoulders are raised above the side of the magazine, when the 30 weight of the assembled series of space-bars forces it over the beveled portion K¹³ of the magazine K into the channel K', permitting it to drop into position in front of the assembling-star H¹³, whereby it is forced into the 35 assembling-box I. The delivery of more than one space-bar at one operation is provided against by means of the studs K¹² on the pivoted cover K¹⁰, (clearly shown in Figs. 27 and 28,) which are squared off and formed 40 in such fashion as to permit the escape of a single space-bar at a time. As before noted, the spring guide-piece H¹⁴ serves to check the too rapid fall of the space-band by reason of its projecting tongue.

45 In order to resist the advance of the lengthening line of matrices and to hold them in compact order, I provide the yielding resistant J, which is forked and straddles the guide-piece J', as clearly shown in Figs. 2 and 6. 50 This resistant J is provided with a finger, which projects down and into the assembling-box, against which the line of matrices and space-bands is assembled. As clearly shown in Figs. 1 and 2, it is connected to the cord 55 or band J², which passes about the compound pulley J³, around which also passes the cord J⁴ to the spring J⁵, attached to the frame of the machine. As will be clearly seen, the 60 tendency of this arrangement is to draw the resistant J to the right and to oppose the enlarging line of matrices and space-bands, 65

which is constantly urged forward by the action of the assembler-star H¹³.

The length of the line is determined by the pawl or detent L, which depends from the 70 slotted rock-shaft L² and which is adjustably attached thereto by the set-screw L³ in such manner that the length of the line may be determined at will. A spring L⁴, attached to the frame of the machine and to the rock-shaft L², tends to force the pawl L forward into the path of the resistant J, but permits the pawl to be swung rearwardly and out of contact with the resistant when the line is 75 full, as shown in dotted position in Fig. 6, so that the line of matrices and space-bars may be shifted to the elevator at the left.

The construction of the assembling-box I is clearly shown in Fig. 6 and consists of a box open at the top and at the two ends, so 80 that the line of matrices and space-bands may pass in and out. It is further provided with shoulders to engage the lower shoulders Y' of the matrices, thereby sustaining them. The space-bands are sustained in the assembling-box by reason of their shoulders Z², which pass over the upper edges of the box. The front of the assembling-box I is provided with a longitudinal slot I' to enable the operator to see the indicating characters which 85 distinguish the matrices. When a complete line of matrices and space-bands has been assembled, the pawl L is moved rearwardly by the operator against the pressure of the spring L⁴, and the line of matrices and space-bands, together with the resistant, is moved 90 manually to the left along the guideway M until it is inserted and received within the elevator N, which when the machine is at rest is normally in line with the guide M and 95 assembling-box I. In effect the guideway M is a mere continuation of the assembling-box. It will be seen that by this arrangement and the simple manual transfer of the composed line I am enabled to dispense with the first 100 line-elevator, the transferring mechanism, and their operating-levers and cams, as illustrated in my Letters Patent Nos. 436,531 and 436,532, previously referred to.

When the elevator descends in the manner hereinafter to be described, the resistant J is left free to return to its original position in the assembling-box by reason of the spring connections J², J³, J⁴, and J⁵, previously described. In this return movement of the resistant J it encounters the bevel L⁵ on the pawl L and effects the rearward movement of the said pawl against the pressure of the spring L⁴, permitting the passage of the resistant J to its original position in the assembling-box. Then the operator may proceed to the composition of a second line, as the operations of justification, locking, casting, slug trimming and delivering, and of the distribution of the matrices and space-bands 115 of the first line are automatically accomplished in the operation of the machine.

The elevator mechanism.—The elevator N, as more clearly shown in Figs. 23 and 24, is formed as a box open at the right-hand side, so as to permit the entrance of the assembled line and provided with the outer plate N², in which is formed a slot to permit of the entrance of the mold proper, O', against the face of the assembled matrices, as clearly shown in Fig. 15. At the other side of the assembled line of matrices the plate N⁸ is provided, which enters between the shoulders Y' Y' at the rear of the matrices and firmly holds them in position, also as clearly shown in Fig. 15. The front plate N², as shown in Fig. 24, is formed with ways or recesses to receive and hold the upper shoulders Y' of the matrices and Z² of the space-bands and to prevent the part Z' of the space-band from rising during the operation of justification, hereinafter to be described.

The plate N⁸ is of hardened steel and is designed to have great strength and firmness, as it receives directly the pressure of the mold and of the pot-mouth acting against the mold. This plate N⁸ is, however, permitted a slight amount of horizontal play as regards the elevator N, so as to permit a slight yield and to insure the exact and certain closing of the mold by the assembled line in the elevator. This slight yielding movement is secured by means of a limited play permitted to the screws N¹⁰, whereby the plate N⁸ is attached to the elevator N, and by the insertion of the springs N⁹ between the plate N⁸ and the elevator-frame, all as plainly shown in dotted lines in Fig. 24.

Pivoted to the elevator at the point N⁶ is a pawl arrangement consisting of the arm N⁵, at the top of which is secured the horizontal solid arm N⁴. A beveled pawl-piece N³ is adjustably secured within this slotted arm, by means of the set-screws N¹¹, in such manner that it may be set throughout the length thereof, so as to secure the proper adjustment for different lengths of line. A spring N⁷, acting upon the arm N⁵, tends to project the beveled pawl-piece N³ forward into the elevator-channel and in the path of the advancing line of matrices, which, however, is enabled to move the pawl N³ rearwardly and to permit of the entrance of the assembled line by reason of the bevel, after which the spring N⁷ restores the pawl to its normal position, holding the line firmly between its end and suitable stop-pieces located within the elevator-channel.

The elevator N is splined upon the vertical shaft N¹² and is free to move thereon. The automatic operating means for the vertical movements of the elevator N upon the shaft N¹² are secured by the chain N¹⁶ and the spring N⁴¹, attached to the elevator N and passing up and secured to the pulley N¹⁷, suitably journaled at the top of the machine. The spring N⁴¹ is employed to permit a slight yield to insure the accurate alinement of the elevator N in its several positions of rest.

Fast to this pulley N¹⁷ is a second and small pulley N¹⁸, from which passes the chain N¹⁹ to the lever N²⁰, fast on the sleeve N²¹, which turns freely on the rod or bearing N²³. Also fast on the sleeve N²¹ is the roller-arm N²², which rests upon and is controlled by the cam N²³, fast upon the cam-shaft N²⁶. (See Fig. 18.) Attached to the frame of the machine 75 and to the arm N²⁰ is the spring N²⁴, which normally acts to depress said arm N²⁰ and through the connections already described to hold the elevator in its most elevated positions. The cam N²³, however, acting upon 80 the roller-arm N²², resists the action of this spring and permits the upward movement of the elevator only at the desired intervals. It will be obvious that other suitable means, such as racks and pinions, may be substituted 85 for the chains and pulleys here described for actuating the elevator without departing from the spirit of my invention.

Normally and when the machine is at rest, as before stated, the elevator N rests in proper 90 registration with the guideway M and the assembling-box I to permit the entrance of the assembled line. It is sustained in this position by the adjusting-screw N⁴⁰, (see Fig. 23,) resting upon the hand-pawl N¹³. (See Figs. 95 1 and 14.) This pawl is located upon the vise-cap and is pressed into the path of the elevator N by a spring N¹⁴ in such manner that it will engage and stop the elevator in its downward movement. The pawl is beveled, as shown at N¹⁵, to permit the passage 100 of the elevator N after the casting and when the elevator rises to the top of the machine to convey the matrices to the distributing mechanism. The pawl N¹³ is strong and simple in construction, has no parts to get out 105 of order, and by reason of the adjusting-screw N⁴⁰ a perfect alinement between the elevator and the assembling-box may always be secured. 110

After an assembled line has been placed in the elevator by the hand of the operator, as before described, the operator disengages the pawl N¹³ from under the elevator, and it sinks by its own weight until the set-screw N²⁷ 115 comes into contact with the base-plate of the machine and stops its further movement. Before, however, the elevator has reached this extreme lowermost position the set-screw N²⁸ has impinged upon and depressed the 120 starting-lever N²⁹, which is attached to the automatic starting-shaft. It will thus be seen that this lowering of the elevator by the hand of the operator starts the operation of the machine and that thereby the further operations 125 are all accomplished automatically in the manner hereinafter to be described. When the elevator is permitted to take this lowermost position, it has entered into and is embraced by the vise-cap P and is firmly held 130 therein during the subsequent operations of the justification and casting. This vise-cap is made in one piece and is of such strength and so rigidly secured to the machine by the

- rods or braces O^4 as to afford all the strength and firmness requisite during the operations of justification and casting. The vise-cap, as shown in Figs. 1 and 14, is connected by 5 the bolts O^4 to the rear portion of the frame of the machine, which rear portion also supports the cam-shaft and the pot-lever S^6 , as shown in Fig. 15. The vise-cap receives the elevator when it is in the casting position.
- 10 During the casting operation the mold is pressed against the matrices with considerable force and the strains thus created are transmitted through the vise-cap and the anchor-bolts O^4 back to that portion of the frame
- 15 supporting the cam-shaft and the cam-levers. The vise-cap is preferably arch-shaped to give it suitable strength. By the employment of this vise-cap, simple in construction yet rigid enough to secure the necessary firmness and
- 20 rigidity, I am enabled to dispense with the vise and vise-frame which I have shown and illustrated in the prior Letters Patent referred to, Nos. 436,531 and 436,532.
- 25 As will hereinafter appear from the further description of the construction and operation of the machine, after the casting has been effected the elevator rises with the line to the top of the machine, where the matrices and space-bands are transferred directly to the
- 30 distributing mechanism. Thus it will be seen that I am enabled to dispense entirely with the swinging arm for transferring the matrices to the distributor, as shown in the prior patents referred to, as the line is always contained in the elevator after its assemblage until it is transferred to the distributor.
- 35 *Assembling and locking mechanism.*—In order to clamp the matrices against each other and against the face of the mold and to secure
- 40 their accurate alinement, I make use of clamping and alining devices which are operated in part by the action of the justifying mechanism, and consequently are to be considered in connection therewith. When the elevator
- 45 N lowers the assembled line of matrices and space-bands in front of the mold and in such position that the linotype or slug is to be cast therefrom, the line is brought in such position that it may be acted upon by the movable jaw R, which is supported upon the vise-cap P and is so shaped that it may enter the elevator N and compress the rear end of the line longitudinally against the fixed jaw R' , also located upon the vise-cap P at the other
- 55 end of the elevator-channel. The jaw R has a spring-actuated movement of its own governed by a cam which will hereinafter be described. It is also arranged so as to be acted upon by a screw-threaded rod Q^8 , supported
- 60 upon the vise-cap and with its end abutting against the rear end of the jaw R and in such position that a rotation of the screw-rod Q^8 will advance the jaw against the line of assembled matrices and firmly lock the same.
- 65 This rotation of the screw Q^8 is normally effected by the arm Q^7 , adjustably fixed to the end of the screw and having its other end at-

tached to the slotted link Q^6 , which is normally pressed upward by means of the spring Q^9 , located upon the main frame. It will be seen from an inspection of Figs. 3, 14, 16, and 17 that unless otherwise prevented the action of the spring Q^9 will normally tend to lift the arm Q^7 , thereby turning the screw Q^8 and advancing the jaw R unless this action be otherwise prevented. However, the action of the spring Q^9 and of the screw Q^8 is governed by the action of the justifying-lever Q' and permitted to act first just before the operation of justification.

The justification of the assembled line is effected by driving up the long wedges Z of the space-bands in a manner somewhat similar to that described in my Letters Patent Nos. 436,531 and 436,532 previously referred to, as well as in a number of other patents granted to me. This driving up of the long wedge Z is effected by the single justification-plate Q, which is attached to the justification-lever Q' . This justification-lever Q' is pivoted upon the rod or bearing Q^4 and is normally urged upward by the action of the powerful spring Q^{15} , (see Fig. 16,) attached to the other end of the lever Q' and to the base of the machine. This upward movement of the lever Q' is, however, resisted and controlled by the action of the justification-cam Q^3 , fast upon the cam-shaft N^{26} , which acts upon a roller on said lever and permits the lever to rise through the force of the spring Q^{15} only at the proper intervals.

When the line of matrices has been placed in front of the mold, as clearly shown in Fig. 3, the justification-cam Q^3 is in the position shown in Fig. 16. The front end of the justification-lever Q' is formed with a pin or projection Q^5 , which enters the slot in the link Q^6 and which when the lever Q' is in depressed position acts to depress the link Q^6 against the pressure of the spring Q^9 and to hold the arm Q^7 , thereby retaining the screw-threaded rod Q^8 in its extreme outward position, as shown in Fig. 3. When, however, the cam Q^3 turns further, as shown in Fig. 16, the lever Q' is permitted to rise slightly, thereby by means of the slotted connection previously referred to permitting the link Q^6 to be raised by the spring Q^9 , the arm Q^7 turned, and the movable jaw R firmly advanced sufficiently to lock the assembled line. This movement of the parts Q^6 and Q^7 is clearly shown in detail in Fig. 17. It will be seen that this locking of the line will take place before the justification-plate Q has been elevated sufficiently to act upon the base of the space-bands Z. After the line is firmly locked in position in the manner above described the plate Q is still further elevated and the justification is effected in the manner now to be described. In my Letters Patent Nos. 436,531 and 436,532 previously referred to the justification is effected by the inclined justification-plate, which acts in various angular positions upon the space-bands, so as to make allowance for

the sidewise movement of the space-bands in the assembled line and to prevent the bending or breaking of the space-bands, which might result from a direct and continuous perpendicular action. In order to effect a similar result and at the same time to enable me to employ a horizontal plate and single actuating mechanism, I construct the cam Q^8 (see Fig. 16) with a series of small waves or corrugations Q^{20} , so that the justification-plate is permitted to advance and act upon the base of the space-bars with an intermittent or jogging motion. The intermittent action of the justifying-plate Q and its slight intermittent retraction permit the space-bands to move laterally as they expand and prevent their breaking or bending, which might occur if the action were continuous and direct. It will be further seen that this construction entirely dispenses with the justification-slide, second justification-lever, and cam and also with the vise-frame shown and described in my previous Letters Patent referred to.

The movable jaw R in addition to the locking motion already described is provided with means for effecting an independent and larger movement in the event of no line or of a short line of matrices being presented to the casting mechanism. It will be seen that the jaw R in its retracted position abuts against the screw-rod Q^8 , but is not connected thereto. Pivotally connected to the jaw R at its rear end is the arm R^2 , rigidly attached to the rock-shaft R^{31} , which is suitably journaled in the main frame of the machine. Rigidly attached to the other end of this rock-shaft R^{31} is the arm R^4 , which, by means of the link R^5 , is acted upon by the lever R^6 , which is normally depressed by the action of the spring R^{10} , attached to the main frame of the machine. This action of the spring R^{10} is, however, controlled by the cam R^8 , fast upon the cam-shaft N^{26} , which acts upon the roller R^7 upon the other end of the lever R^6 . At the proper intervals the configuration of the cam R^8 permits the spring R^{10} to depress the lever R^6 and through the connections described to turn the arm R^2 and advance the movable jaw R , so as to close entirely or partially the face of the mold in the event of no line or a short line having been presented in front thereof, thereby preventing squirting of the molten metal and the consequent disadvantages thereof. It will be seen that this movement of the jaw R is determined accurately and at the proper time by the direct control of the cam R^8 and that this arrangement practically obviates the dangers of squirting. A spring R^9 is also provided, attached to the arm R^4 and the end of the lever R^6 , so as to permit the insertion of links R^5 of varying lengths and to give a yielding connection and also to permit of the insertion of blocks of varying sizes between the screw-rod Q^8 and the abutting end of the jaw R when it is desired to change the length of line or for other reasons.

It is to be noted that in the present form of construction but one of the two jaws is made movable and that the one at the rear end of the line. This is the natural arrangement, as the inequalities and shortcomings in the assembled line are mainly at the rear end thereof, and the movable jaw in this instance is arranged to act at the rear end. Further, by this arrangement the composition of short or "paragraph" lines is facilitated, the general and present arrangement being the assembling of such lines with a number of blank matrices. Other advantages will appear in the periodic and positive closing of the mold in the case of short lines or when no line is presented, thus almost certainly avoiding "squirts." It will also be seen that the arrangement of the jaw-actuating mechanism is such as to permit the justification to proceed without encountering the resistance of the jaw.

The mold mechanism.—In the form of machine which I have illustrated in the present application I prefer to employ instead of the mold-disk formerly employed a mold sector or carrier O , as clearly shown in Figs. 3, 15, 20, and 21. The mold-carrier O is provided, as is shown, with the mold proper, O' , inserted in the mold-sector and adjustably secured therein in such manner that molds of varying shapes and sizes may be substituted in the manner well understood in the art. The mold-sector O is rigidly attached to the end of the longitudinally-movable and rotatable shaft O^2 . This shaft O^2 is suitably journaled in the mold-frame O^3 , which is supported upon the lever rod or shaft N^{25} and also upon the vise-cap braces O^4 O^4 . The chief advantage in this arrangement of the mold-shaft and mold-frame is that the mold-shaft and mold-carrier are placed above the pot, thereby avoiding the clogging of metal in case of squirts and making all of the parts more visible and free for access and avoiding the necessity of removing the vise-frame now employed. Keyed to the other end of the shaft O^2 is the bevel-pinion O^5 , which when the mold-shaft O^2 is in its rearward position is adapted to be engaged and to be moved by the mutilated gear O^6 , fast upon the cam-shaft N^{26} . The rotating movements of the mold and mold-shaft are two, one movement of ninety degrees from the ejecting position to the casting position, which is effected by the gear-teeth O^7 on the gear O^6 , and another movement of two hundred and seventy degrees from the casting position back to the ejecting position, which latter movement is effected by the gear-teeth O^8 on the gear O^6 . Both of these movements are imparted to the mold-shaft and to the mold-carrier when the mold-shaft is in its longitudinally-rearward position, and consequently when the mold O' is out of engagement with the matrices and the elevator.

The longitudinal movement of the mold-shaft O^2 referred to is secured by means of the lever O^{11} , pivoted to a collar O^{21} , fast on

said mold-shaft within the mold-frame. The lever O^{11} is pivoted upon the rod or shaft Q^4 and is provided with a roller O^{12} , which engages the grooved cam O^{13} , fast on the shaft 5 N^{26} and so shaped and timed that the proper advance and rearward motions of the mold-shaft O^2 are imparted thereto at the proper intervals. Also fast on the shaft O^2 is a steel arm or bushing O^9 , which is adapted to engage with either of the two pins $O^{10} O^{10}$. One of these pins O^{10} corresponds with the angular position of the mold-shaft O^2 when the mold is in the casting position, and the other of the pins O^{10} corresponds with the angular 10 position of the shaft O^2 when it is in the ejecting position. When the mold is turned to either of the positions mentioned and the mold-shaft is then longitudinally advanced, it will be seen that the respective pin O^{10} will 15 enter and engage the arm O^9 , thereby firmly holding the mold-shaft and mold in proper position. This arrangement enables me to dispense with the centering or adjusting pins and recesses formerly employed by me upon 20 the face of the mold-disk.

The pot and pump mechanism.—The pot S is pivoted at S^2 in the base-frame of the machine and may be of any improved or desired construction—such, for example, as is 25 shown in my Letters Patent Nos. 436,531 and 436,532 or in the other numerous Letters Patent granted to me. As shown in Fig. 15, however, it is provided with the gas inlets or burners $S^3 S^3$ and with the pump-plunger S^8 . 30 It is further provided with the pot-mouth S' , which may be of any desired construction and which is adapted to engage and impinge against the rear face of the mold proper, O' , when the mold-carrier O and the pot S are 35 forcibly moved against the line of matrices assembled in the elevator for the purpose of casting the slug or linotype. This forward motion of the pot S about its pivot S^2 is effected by the pot-cam S^7 , fast upon the cam-shaft N^{26} , which acts upon the rear end of 40 the pot-lever S^6 , journaled upon the rod or shaft Q^4 , with its fulcrum in such position as to give the pot a forward and lifting movement. The forward end of the pot-lever S^6 45 acts upon the pot-link S^4 , which is pivoted directly to the pot S , and a spring S^5 is interposed between the pot-lever S^6 and the pot-link S^4 in order to insure the even pressure of the pot-mouth on the mold and to prevent 50 the breakage of parts.

The pump-plunger S^8 is pivoted to the pump-lever S^9 , which is pivoted on the lever rod or shaft N^{25} . The spring S^{10} , attached to the lever S^9 and to the base of the machine, 55 tends to depress the pump-plunger S^8 and to eject the contained molten metal from the pot-mouth. This action of the spring S^{10} , however, is controlled by the pump-cam S^{12} , fast upon the cam-shaft N^{26} , which, acting upon the cam-roller S^{11} , permits the action of the spring S^{10} and the ejection of the metal only at the proper time.

Ejecting mechanism.—The ejector-blade S^{14} , which is employed to eject the slug or linotype from the mold, is attached to the 70 ejector-slide S^{13} by the screws S^{16} . It will be seen that the screws S^{16} permit of the ready removal of the ejector-blade S^{14} and of the substitution therefor of a different ejector-blade, as may be required for a different 75 length of line. The ejector-slide S^{13} is guided in the ejector-frame S^{15} , which is carried by the mold-shaft O^2 and upon one of the vise-cap braces O^4 , being adjustably supported thereon by means of the adjusting device S^{60} , 80 so that the blade may be readily adjusted in position with the mold. The mechanism for imparting the proper ejecting movements to the ejector-blade S^{14} consists of the link S^{17} , pivoted to the ejector-slide S^{13} and to the 85 ejector-lever S^{18} , journaled on the lever shaft or rod N^{25} . The lever S^{18} carries a roller S^{19} , which is acted upon by the ejector-cam S^{20} , fast on the cam-shaft N^{26} . The cam S^{20} is so shaped and timed as to give the ejector-blade 90 S^{14} the proper movements to conform it with the movements of the mold-shaft O^2 as well as to actuate it suitably for the ejecting purposes and thereafter to retract it from the mold. The ejecting movements proper are 95 two in number and consist, first, of a slight forward movement which partially ejects the slug from the mold and permits it to remain in this position long enough for one of its forward edges to be trimmed by the descending 100 trimming-knife S^{22} , hereinafter to be described. After this the second ejecting movement is accomplished, whereby the linotype or slug is ejected entirely from the mold and into the knife box or block S^{24} , hereinafter to 105 be described.

Trimming mechanism.—The trimming mechanism for removing the surplus metal from the slugs or linotypes and for reducing them to proper form consists, essentially, of 110 three knives. The first operation, which is the trimming of the base of the slug or linotype, is effected by the knife S^{21} . (See Figs. 20 and 21.) This knife S^{21} acts upon the base of the linotype or slug while it is still in the 115 mold and the trimming is effected by reason of the rotation of the mold-carrier O from the casting to the ejecting mechanism. As the mold-carrier O makes this partial revolution the base of the slug is carried by and against the knife S^{21} and the shaving is thus effected. The knife S^{21} is adjustably mounted by the 120 adjusting-screws S^{55} upon the mold-frame O^3 .

The second trimming operation is performed by the knife S^{22} , which is moved along 125 one of the front edges of the slug or linotype after the latter has been partially ejected from the mold and while it is retained there until the knife S^{22} has had time to complete its operation. The knife S^{22} is attached to 130 the knife-rod S^{23} , which is pivotally attached to the link S^{25} , which slides upon the vertical shaft S^{24} . A link S^{26} , attached to the knife-rod S^{23} , connected to the spring S^{27} , which

bears upon the link S^{25} , tends to keep the knife-rod S^{23} in constant engagement with the mold O' , as clearly shown in Figs. 9, 11, and 12, thereby insuring always an exact parallelism of the knife movement with the face of the mold and obviating the necessity of adjustment for different thicknesses of slugs or linotypes, which is necessary only for the knife that trims the other edge of the linotype or slug and which will be hereinafter described. The link S^{25} is connected to a second link S^{28} , (see Figs. 1 and 22,) which in turn is connected to the knife-lever S^{29} , pivoted upon the rod or shaft Q^4 . The lower end of the knife-lever S^{29} is acted upon by the spring S^{30} , attached to the base of the machine, and which tends to constantly raise the knife-rod S^{23} and the knife S^{22} . This action of the spring S^{30} is, however, governed by the knife-cam S^{31} , fast upon the cam-shaft N^{26} and acting on a roller on the lever S^{29} , which cam S^{31} is so shaped and timed as to effect the downward movement of the knife-rod S^{23} and its attached parts only at the proper times.

Referring more particularly to Figs. 1, 9, 10, 11, 12, 13, and 22, the trimming of the other front edge of the slug or linotype will now be described. After the knife S^{22} has traversed one of the front edges of the slug and is freed therefrom the ejector-blade S^{34} acts to entirely eject the slug or linotype into the knife box or block S^{34} , which is mounted on the vise-cap and under the piece S^{35} , which is pressed downward by the spring S^{36} . The other side of the receptacle, into which the slug or linotype is thus forced, is formed by the wedge-shaped piece S^{44} , (see Figs. 10, 11, and 13,) which constitutes the adjusting means employed for adapting the knife block or box S^{34} to different thicknesses of slugs. The position of the wedge S^{44} is governed by the adjusting - screw S^{45} , journaled in the frame of the knife block or box and which may be turned to insert or retract the wedge S^{44} , so as to adjust it to different thicknesses. Also carried by the wedge S^{44} is the set-screw S^{46} , which is permitted a longitudinal movement by reason of a slot in the frame of the knife-block S^{34} and which may be turned up to hold the wedge in its adjusted position. After the slug has been passed into the knife block or box and under the spring-pressed piece S^{35} it is moved longitudinally by the slug-shifter S^{32} , which is attached to the link S^{25} of the knife-rod. The knife-cam S^{31} through the connections already described still further depresses the knife-rod S^{23} , and with it the slug-shifter S^{32} , in such manner that the slug is carried from under the spring-pressed piece S^{35} , under the spring-pressed piece S^{37} , under the trimming-knife S^{39} , and under the spring-pressed piece S^{42} , until finally it is dropped into the galley or chase S^{48} . The spring-pressed piece S^{37} corresponds to the spring-pressed piece S^{35} , save that it is acted upon by a more powerful spring S^{38} , which is desirable to hold the slug or linotype firmly in position while it is being trimmed. The third spring-pressed piece S^{42} is acted upon by the spring S^{43} , which is designed to correspond in strength with the spring S^{38} to insure the firm holding of the slug during trimming. It will be seen that the spring S^{36} need not be of the same tension, as its object is merely to hold the piece S^{35} and the slug or linotype until the action of the descending slug-shifter forces the slug under the trimming - knife and the spring-pressed pieces S^{37} and S^{42} . The knife S^{39} is suitably mounted in the frame of the knife box or block S^{34} and may be set up or adjusted by means of the adjusting-screws S^{40} . When the slug has been forced past the third knife S^{39} , it will be seen that it has been trimmed at the base and at both of its forward edges and that it is dropped into the chase or galley S^{48} in every respect suitable and ready for the purposes of printing therefrom. When the slug has been deposited in the chase or galley S^{48} , it is acted upon by the pivoted finger S^{49} , whose lower end is actuated by the lower end of the link S^{28} in the extreme lower movement of the knife-lever S^{29} . A spring S^{55} may be employed to return the finger S^{49} to its normal position. The linotype or slug is thus shifted and assembled with the previous linotypes or slugs deposited in the chase or galley in suitable order and form for printing.

Distributing mechanism.—The distributing mechanism consists fundamentally of a horizontal bar having thereon horizontal ribs or teeth to engage and sustain the matrices, the teeth being permuted, like those of the matrices, so that as each matrix is passed lengthwise of the bar it will be suspended by one or more pairs of teeth until it arrives at a point immediately over the upper magazine-channel, at which time it will disengage from the bar and fall by gravity.

The present distributor is substantially equivalent to that shown and described in my Letters Patent No. 347,629, granted August 17, 1886, and also in the Letters Patent Nos. 436,531 and 436,532, previously referred to.

When the elevator N has risen to its uppermost position in the machine in the manner already described, it carries with it the assembled line of matrices and space-bars from which the casting has been made and is finally arrested by the pin N^{42} in such position that the line of matrices and space-bars may be moved lengthwise therefrom by means of the shifter W . This shifter W is suitably guided in the vicinity of the distributor-box and is free to slide upon the slide or guide way W^2 . (See Figs. 1 and 4.) The shifter W is actuated at suitable intervals by reason of its connection to the shifter - lever W' , which is fixed upon the rock-shaft W^3 , journaled in the main frame of the machine and provided at its other end with a roller-arm W^2 . (See Figs. 1 and 22.) A spring W^7 tends normally to depress the arm W^2 and to move the lever-arm W' inward and to the right,

thereby causing the shifter W to engage the line of matrices in the elevator N and to remove them therefrom by a gradual and gentle pressure. Acting upon the roller-arm W² 5 is the cam W⁸, fast upon the cam-shaft N²⁶, and which acts upon the roller-arm W² in such manner as to return the shifter W to its extreme outward or left-hand position and to leave it in readiness for a new inward traverse through the elevator N. When the shifter W starts to move the line of matrices and space-bars from the elevator N into the distributor-box W²⁰, which is shown partly broken away in Fig. 4, it will be seen that 10 the upper ears Y' Y' of the matrices will be engaged and supported by correspondingly-cut channels in the sides of the distributor-box W²⁰ and that the upper ears Z² of the space-bands will pass upon and be sustained 15 by the upper edges of the sides of the distributing-box W²⁰ as the line traverses the box. As the line of matrices is forced inwardly the matrices will be forced upon the grooved bar W¹⁰, which will be engaged by 20 the matrices by reason of their formation with the sustaining-teeth Y². This bar W¹⁰, unlike the distributor-bar X²⁹, is not provided with the permuted ridges, but is designed 25 simply to support the matrices in their passage to the distributing mechanism proper. Also formed in the sides of the distributing-box W²⁰ and connected with the guideway or space-bar channel U are inclined grooves W¹¹, (see Figs. 4 and 32,) which are designed 30 to receive the upper ears Z² of the space-bands Z as the line is moved to the right and to permit the space-bands to pass into the space-band channel U, whence they pass to their 35 original position in the space-band box K. This passage of the space-bands through the box W²⁰ and of its ears Z² through the ways or channels W¹¹ will be readily apparent from 40 an inspection of Figs. 4 and 32, it being understood that the line is being moved to the right under the pressure of the shifter W and that the matrices are at the same time engaged and supported by the engagement of the grooved bar W¹⁰ with the teeth Y² of the matrices. The channel-way U is shown as 45 provided with a curved guide-plate U³, which is designed to act upon and to guide the lower end of the space-bars Z in the manner clearly shown. The space-band channel U is also provided with a plate U', pivoted at U² and held in position by the pin U⁴. The disengagement of this pin U⁴ permits the turning of the plate about its pivot and gives access to the channel-way U. When the shifter W has moved the matrices inwardly, the matrices are then in a position to be engaged one by one by the vibrating finger X' and raised into position to be severally engaged by the continuous screws and moved along the distributor-rail proper. This finger X' is pivoted to an elbow-lever X² and normally drawn inward by the spring X³ against a portion of the frame X¹² in such position that it may en-

gage and raise in its upward movement one matrix at a time as the line is pressed inward by the shifter. 70

The pivoted elbow-lever X² is connected to the pivoted lever X⁴ by means of the spring X⁵, which permits a certain amount of play between the parts and prevents breakage in the event of a matrix being caught or jammed 75 while the finger or dog X' is acting upon it. Motion is imparted to the arm X⁴ by the grooved cam X⁶, which is fast on the shaft X⁷ of the screw X¹⁰.

The screw X¹⁰, its shaft X⁷, the cam X⁶, and 80 the actuating-gear X¹⁶ are carried in a frame X¹⁸, which is pivoted upon or carried by a shaft X¹⁴ in such manner that they may be swung upwardly and free from engagement with their connected parts in order to permit 85 of ready access to the distributor-bar. When lowered into operative position, these parts are held firmly in place by the spring-pawl X¹⁵.

When the matrix is raised by the vibrating dog X' over the shoulder of the guide-piece 90 X⁸, the upper shoulders Y' Y' of the matrix are engaged by the square thread of the longitudinal screws X⁹ and X¹⁰, and one of the lower shoulders Y' is engaged by a third screw X¹¹, these screws being positively revolved in 95 the proper direction to carry the matrices along the distributor-rail X²⁹, with which the teeth of the matrices engage to the points at which they fall therefrom. The screws are timed in their revolution so that the ends of 100 their threads pass behind and engage each matrix as soon as it has passed over the shoulders of the guide-piece X⁸, the screws serving not only to advance the matrices, but to maintain a separation between them as they 105 are advanced along the rail. When a matrix has arrived at its proper channel, its teeth will become disengaged from the distributor-bar X²⁹, according to the permutations of 110 the teeth and bar, in the manner well understood, and the matrix will drop between the partition-plates B⁹ into its proper magazine-channel. The distributor-bar X²⁹ is held in position in the upper frame of the machine by the screws X³³, and the screws X³⁴, against 115 which the distributor-rail abuts, permit of its ready vertical adjustment.

Motion is imparted to the screw-shafts in the following manner: Journalized at one end of the distributor-frame is the short shaft X²¹. 120 Loose on this shaft is the band-pulley X²³, which is constantly driven by the cross-belt X²⁷, which passes around the pulley X²⁸, fast upon the intermediate shaft H²⁵, previously referred to. Splined to the shaft X²¹, but capable of a slight longitudinal movement thereon, is the clutch member X³⁰. This clutch member X³⁰ is normally pressed into contact with the band-pulley X²³ by the spring X²², which is interposed between the clutch member X³⁰ and the disk X³¹ at the end of the shaft X²¹. It will be seen that normally the bearing-face X³⁴ of the clutch member X³⁰ will be forced into frictional contact with the band- 125 130

scribed the other operations of the machine are not constant, but intermittent, and consequently power will be applied to them only at the necessary intervals. Splined to the 5 power-shaft T is the spring-clutch member T⁴, which may be of any desired or customary construction and which is designed to impart motion to the shaft T by reason of its engagement with the band-pulley T² T³ at the desired intervals. A spring T⁵, acting upon 10 the clutch member T⁴, tends normally to press the clutch member T⁴ inward and connect the shaft T to the band-pulley T² T³. At the other end of the shaft T is a pinion T⁶, (see 15 Figs. 18 and 19,) which meshes with the gear-wheel T⁷, fast upon the cam-shaft N²⁶ and whereby the power is imparted thereto when necessary. The clutch member T⁴ is embraced or straddled by the bifurcated arm T⁸, 20 (see Figs. 3 and 19,) which is pivoted at T⁹ near the base of the machine and is rigidly attached to the arm T¹⁰, which is also pivoted at T⁹. At the other end of the arm T¹⁰ is pivoted a link T¹¹, having a hooked end and 25 which when the cam-shaft is at rest is sustained vertically by the pin or piece T¹², formed upon the side of the gear-wheel T⁷. It will be seen from an inspection of Fig. 19 that in this elevated position of the link T¹¹ 30 the spring T⁵ will be pressed outwardly and the clutch member T⁴ disengaged from the band-wheel T² T³, and that when the link T¹¹ is disengaged from the piece T¹² the weight of the link T¹¹ and of the arm T¹⁰ will release 35 the arm T⁸ and permit the pressure of the spring T⁵ to clutch the clutch member T⁴ with the band-pulley T² T³, thereby imparting motion to the power-shaft T and cam-shaft N²⁶.

Starting and stopping mechanism.—Journaled near the base of the machine is the starting-shaft T¹³. (See particularly Figs. 3, 18, and 19.) Fast upon the front end of this shaft is the starting-pawl N²⁹, previously referred to. The other end of the shaft is provided with a 40 finger T¹⁴, so located as to act upon the link T¹¹. It will be seen that when the elevator N has descended and the set-screw N²⁸ has contacted with the starting-pawl N²⁹ (see Figs. 18 and 19) the shaft T¹³ will be turned and 45 that the finger T¹⁴ will move the link T¹¹ from engagement with the pin T¹², thereby permitting the release of the parts and the clutching of the shaft T to the band-pulley T² T³ in the manner previously described. A spring 50 T¹⁵ normally presses the link T¹¹ toward the gear-wheel T⁷, and when the gear-wheel T⁷ has made a complete revolution the pin T¹² will hook under and engage the hooked upper end of the link T¹¹, thereby raising it 55 against the force of the spring T⁵ and unclutching the clutch member T⁴ and bringing the power-shaft T and cam-shaft N²⁶ to rest, and the contact of the link T¹¹ with the finger T¹⁴ will reset the starting-pawl N²⁹. 60

65 I have also provided a second starting and stopping mechanism which may be manually operated and which permits the operator to

stop the operation of the cam-shaft at any desired point and to start again. This consists of the pivoted elbow-lever T¹⁶, located at the 70 front of the machine and connected by the link T¹⁸ to an arm T¹⁹, which is fast upon the rock-shaft 21. The other end of this rock-shaft T²¹ is provided with a finger T²², which passes under and engages with a pin T²⁰ at 75 the side of the link T¹¹. It will be seen that when the pin N²⁸ on the elevator N has operated the starting-pawl N²⁹ and the link T¹¹ and arm T¹⁰ have been permitted to drop through the connections already described the pin T²⁰, 80 acting upon the finger T²², will turn the rock-shaft T²¹ and lower the arm T¹⁹, which through the link T¹⁸, acting on the elbow-lever T¹⁶, will lower the lever T¹⁶ to horizontal position, as shown in Fig. 1. If the operator desires 85 to stop the machine at any time during the locking, justifying, casting, and trimming actions, it is necessary for him simply to elevate the hand-lever T¹⁶, which, acting, through the connections described, by the finger T²² 90 upon the pin T²⁰, raises the link T¹¹ and through the further connections described compresses the spring T⁵ and unclutches the clutch member T⁴, stopping the power-shaft T and the cam-shaft N²⁶. To restore the 95 operation, it is necessary only to again lower the hand-lever T¹⁶ to its horizontal position, when the parts will resume their operative position, as described, and the cam-shaft will continue to operate until the clutch member 100 is again thrown out, either automatically by the action of the pin T¹² on the hook end of the link T¹¹ or by a repeated upward movement of the hand-lever T¹⁶.

Operation.—The various parts of the machine having been now described, their operation will be understood to proceed in the following order: The operator depresses successively the finger-keys D, which represent the desired characters, and thereby causes the 105 matrices to be discharged from the mouth of the magazine B, thence through the channels G to the belt H, on which they are delivered one after another in an upright position and side by side into the assembling-block I, in which they are advanced in close order by the assembling-star H¹³, acting against the last matrix. From time to time 110 space-bars are delivered into the line by means of the finger-key K² through the 115 mechanism before described. After the composition of the line is completed the operator 120 manually pushes back the pawl L and moves the line manually to the left until it is contained within the elevator N, after which the 125 operator turns the elevator-pawl N¹³ in such manner as to permit the elevator to descend and to permit the yielding resistant J to be returned to its original position in the assembling block or box I, when the operator may 130 proceed to the assembling and composition of a second line. When the elevator has lowered to the casting position and the line is in proper position before the mold, the cam-

pulley X^{23} by means of the spring X^{22} and that the shaft X^{21} will be continuously driven. At the end of the shaft X^{21} is the pinion X^{20} , (see Fig. 34,) which gears into and turns in their proper direction both the pinions X^{18} X^{19} , which are fast, respectively, upon the shafts of the screws X^9 and X^{11} . Upon the shaft of the screw X^9 there is a second pinion X^{17} , which gears into the corresponding pinion X^{16} , which is fast upon the shaft of the screw X^{10} . It will be seen that through the connections described a continuous motion will be imparted to the three screws X^9 X^{10} X^{11} .

It sometimes happens that a matrix in falling from the distributor-bar X^{29} may become lodged between the lower distributing-screw X^{11} and in the magazine-entrance or that it will in the course of its descent assume some other improper position. When this occurs, it is desirable to prevent the breaking or bending of the matrix or of the partition-plates B^9 , that the distributing mechanism should be stopped. In order to effect this stoppage of the distributing mechanism, I make use of a simple stopping device, which is actuated from the free ends of the partition-plates B^9 , which rest in the serrations of the rack B^{13} , as previously described. The rack B^{13} is rigid; but I provide a second serrated rack B^{15} and locate it at the side of the rack B^{13} , into the kerfs or serrations of which the free ends of the partition-plates B^9 also pass. (See Figs. 29, 30, and 31.) The right-hand end of this rack B^{15} is provided with a depending lug B^{16} , which rests upon and normally keeps in its lowermost position the arm B^{17} of the rock-shaft B^{20} against the pressure of the spring B^{19} . The rock-shaft B^{20} is also provided with a pin-arm B^{18} , which in its normal position is kept lowered and out of engagement with the clutch-disengaging mechanisms now to be described.

The clutch member X^{30} is provided with the lateral inclined faces X^{25} and with the stop-pins X^{26} . Assuming now that a matrix should become lodged in the channel-mouth or that it should assume an improper position therein, it will be apparent from an inspection of Figs. 29, 30, and 31 that it will still be engaged at some portion of its periphery by the rotating screw X^{11} , which in its continuous movement will tend to advance the matrix, and consequently the partition-plate B^9 , against which the matrix impinges. This movement of the partition-plate B^9 will consequently be imparted to the rack B^{15} and will move the depending lug B^{16} beyond and out of engagement with the arm B^{17} on the rock-shaft B^{20} . Thereupon the spring B^{19} forces the arm B^{17} upward, turns the rock-shaft B^{20} , and raises the pin-arm B^{18} . The pin of the arm B^{18} will come in contact with one of the side faces X^{25} of the clutch member X^{30} and as the latter rotates will force the same longitudinally to the right, disengaging the clutch-surface X^{24} from the driving-pulley X^{23} . One of the stop-pins X^{26} will

in the course of its rotation come into contact with the pin on the arm B^{18} and will check the further motion of the shaft X^{21} , which may be due to momentum. It will be seen that the operator may then disengage the misplaced matrix and the parts may be restored to their normal working position, as before.

The distributor-box, which consists of the guide W^9 , side pieces W^{20} , and grooved bar W^{10} , is detachably secured in position by the pin W^{201} , the other end of the box being inserted in the bracket or piece X^{12} of the distributor-frame, as shown by dotted lines in Fig. 4.

If it should be desired to cast a second line from the same line before distributing, it is necessary to hold the shifter W out of action, so that the matrices and space-bands may return with the elevator N to its normal position. This I accomplish by providing the arm W^4 on the rock-shaft W^3 with a retaining-pawl W^5 , adapted to engage a stud W^6 on the frame of the machine and within convenient reach of the operator. It will be seen that when so engaged the shifter W and the arm W' will be retained in their outward position, and that consequently the assembled line will return with the elevator N to its normal position, when by releasing the pawl W^5 a second line may be cast in exactly the same manner as the first, and this operation may be repeated as often as may be desired.

It is called to attention that in Fig. 4 the shifter W is shown as transferring one line to the distributor and that a portion of a second line is shown as ready to be engaged by the vibrating dog X' . This would not ordinarily occur in practice, except possibly in the case of very long lines, as the shifter W does not return to its outward position until the full line is in the distributor, as it is by the pressure of the shifter that the matrices are shoved forward, so as to be engaged one at a time by the vibrating dog X' . The showing, as given in Fig. 4, is made for purposes of convenience in illustration.

Driving mechanism.—Motion is imparted to the various parts of my machine in the following manner: Loose upon the power-shaft T is the loose pulley T' , upon which the power-belt runs when the machine is not being operated. Located at the side of the loose pulley T' and also loose upon the shaft T is the compound pulley $T^2 T^3$. A belt T^{22} transmits power from the portion T^3 of the last-named pulley to the pulley T^{31} , which is fast upon the intermediate shaft H^{25} , which carries the pulleys H^6 and X^{28} , which, as already described, transmit power to the assembling and distributing mechanisms. It will be apparent that whenever the power-belt is shifted onto the portion T^2 of the pulley $T^2 T^3$, through the belting and connections described, a continuous operation of the distributing and assembling mechanisms will be secured; but for the reasons already de-

shaft is started through the connection described and the first operation is the closing of the movable jaw R, through the medium of the screw Q⁸, in the manner previously described, thereby determining the exact length of line. At this same period the mold-carrier O has moved longitudinally and the mold-proper, O', has entered the elevator and inserted itself firmly between the upper and lower shoulders Y' of the assembled matrices, as clearly shown in Figs. 15, 16, and 17. Then the justification of the line is accomplished in the manner previously described, and after the line is justified the jaw-lever R² starts to move the sliding jaw R, thereby adding compression to the assembled and justified line of matrices. If a full line of matrices be presented, the resistance of the line will prevent the sliding jaw R from closing. In the event, however, of no line or only a partial line of matrices having been presented the jaw R will close in and prevent the squirting of the molten metal. It will be seen that when a complete line of matrices is presented the jaw will be arrested, for the reason that its inward movement is effected through the medium of a spring R¹⁰. Next the justifying-plate Q starts back and the lock opens; but the pressure of the spring R¹⁰, through the connected parts on the sliding jaw R, prevents the space-bands from dropping and destroying the justification already effected. At this point the elevator is given a slight upward movement through the parts already described, the object of this upward movement being to firmly lift all of the matrices in the assembled line, so as to effect their proper alinement by reason of the contact of the lower shoulders Y' Y' of the matrices with the bottom of the mold O'. After this the sliding jaw R is again locked in position by the turning up of the screw-threaded rod Q⁸ through its connections to the justifying-cam Q³. At this time the pot moves back a small distance to relieve the pressure and permit of the straightening up and to effect the exact lateral contact of the matrices, so as to insure the complete closing of the line. This precaution is taken to permit the absolute straightening of the matrices, which might not be so readily accomplished if the pot-pressure were still applied to the face of the line. Then the pot moves back to its operative position, being held there by the engagement of arm O⁹ with pin O¹⁰, and the pressure of the pot-mouth S', acting on the mold O', firmly locks and holds the line of matrices in position against the steel face-plate N⁸ of the elevator, the vise-cap P assuming the pressure. The parts are now ready for the casting, and the pump-plunger S⁸ starts down and ejects the molten metal into the mold O' and against the face of the matrices, forming the slug or linotype in the mold with the desired characters upon their face. Then next the pump-plunger S⁸ moves upward and the strain on the matrices is re-

lieved. The pot moves backward, the locking of the sliding jaw R by the screw Q⁸ is relieved, and the sliding jaw is retracted by 70° the action of the jaw-lever R². After this the mold starts back and the elevator N moves up to the top of the machine with the matrices and space-bars for distribution. At the same time the mold-disk O makes a revolution of two hundred and seventy degrees to the ejecting position and moves forward longitudinally and is locked in place in this position by the engagement of the pin O¹⁰ with the steel arm O⁹ on the mold-shaft O'. During this rotation of the mold-sector the base of the slug has been trimmed by the knife S²¹. Then the ejector-blade S¹⁴ partially ejects the linotype from the mold to the extent of about one-eighth of an inch and the trimming-knife S²² descends and trims one of the forward edges of the slug in the manner previously described. After this the ejector entirely ejects the slug or linotype from the mold and into the knife block or box S³⁴. The slug-shifter S³² then descends, carrying the slug past the last trimming-knife S³⁹, which trims its remaining edge, and the slug or linotype is then deposited in the galley or chase S³⁶ and moved over by the vibrating finger S⁴⁹. The mold-shaft has in the meantime moved forward and freed its arm or bushing O⁹ from engagement with the pin O¹⁰, whereupon the mold turns through ninety degrees back to its original casting position. In the meantime the elevator N has carried the line of matrices and space-bars to the distributing mechanism at the top of the machine and the shifter W has moved the matrices and space-bars into the distributor-box, from which they will be distributed in the manner already described, when the shifter W resumes its outward position. The elevator N has already descended until it rests upon the elevator-pawl N¹⁸, the automatic operation of the cam-shaft has stopped through the lifting of the arm T¹¹ by the pin T¹² on the gear T⁷, and the consequent disengagement of the clutch T⁴, already described, and the parts are in readiness for a fresh series of operations.

It will be understood while I have herein described springs for operating the various portions that weights may be employed as equivalents and that the details of the driving mechanism and of the elevator mechanism and of the other mechanism may be variously modified at will without departing from the spirit of my invention, provided only they are adapted to impart the requisite movements to the operative parts.

In order to change the parts so that a different length of line may be obtained, it is necessary simply to change the adjustments of the assembler-pawl L of the elevator-pawl N³ and of the movable jaw R by inserting blocks of different length between the jaw and the locking-screw Q⁸, and also to substitute a different ejector-blade S¹⁴ and to insert

a different mold or mold-liner in the mold-carrier O.

In order to change the parts of the machine so that a slug of greater or less thickness may be secured, it is necessary merely to change the adjustment of the wedge S⁴ of the knife-block in the manner previously described and to insert a mold of the required depth in the mold-carrier O.

10. It will be seen that my machine as herein described and illustrated is one of cheap and simple construction, that it has few parts, and that its adjustments and construction are so simple as to enable it to be attended to by an operator without the service of an additional machinist.

I claim—

1. The combination with the matrix-magazine and a pair of slotted plates arranged along and adjacent to the upper end of the magazine, of the partition-plates forming the magazine-mouths, said partition-plates having portions which pass through the slotted plates, and a rod passing through openings in the partition-plates between the slotted plates.

2. The combination with the matrix-magazine and a pair of slotted plates arranged along and adjacent to the upper end of the magazine, of the partition-plates forming the magazine-mouths, said partition-plates passing through the slotted plates, a rod passing through holes in the partition between the slotted plates, and a fixed bar arranged over said partition-plates.

3. The combination with the magazine, of partition-plates forming the mouths of the magazine, means for securely holding said partition-plates at one side of the magazine and a fixed toothed bar at the other side of the magazine, said partition-plates resting upon said bar and having room for limited movement between the teeth thereof.

4. The combination with the magazine and the partition-plates forming the mouths of the magazine, of means for holding said plates at one side of the magazine, and a pair of toothed bars at the other side of the magazine, one of said bars being fixed and the other movable and the partition-plates being engaged by the teeth of said bars whereby the said partition-plates are normally held in position over the magazine-partitions.

5. The entrance-plate supported upon the frame of the machine and capable of a lateral movement thereon, combined with a spring attached to said frame and to said entrance-plate, and an adjusting-screw, so that a constant and accurate adjustment of the magazine and assembling-channels may be secured.

6. The combination with the entrance-plate mounted on the frame of the machine and capable of a lateral movement thereon, and the guide for the escapement-rods attached to said entrance-plate, with a spring connected to the entrance-plate and to the machine-frame, and

with an adjusting-screw, so that a constant and accurate adjustment may be secured between the magazine and assembling-channels and between the escapement-rods and the finger-key mechanism.

7. The matrix carrying and delivering belt combined with pulleys for carrying said belt, which pulleys are suitably actuated, and the lower two pulleys of the series being so located as to incline the lower portion of the belt at such an angle as to insure the delivery of the matrix in the proper position, together with a spring or yielding piece, said piece and belt being so arranged that the matrix passes between them to further insure the delivery of the matrix in the proper position.

8. In combination, the traveling belt, a pulley at the upper end of said belt, means embracing a hand-clutch for actuating said pulley, and two pulleys at the lower end of said belt so located as to angularly incline its lower end.

9. In a linotype-machine, an assembling-belt passing around a series of pulleys, one of which is suitably actuated to move the belt, an assembling star-wheel, and gearing between one of said pulleys and the star-wheel, 95 said gearing including a friction clutch or coupling adapted to slip when the star-wheel is obstructed, for the purpose set forth.

10. In a linotype-machine, the space-band box or magazine comprising a pivoted cover adapted to be swung back to expose the upper ends of the space-bands, a stop against which said cover rests when closed, and suitable shoulders or projections on the cover arranged to prevent more than one space-band from being ejected at a time.

11. In a linotype-machine, a space-band box or magazine comprising guides upon which the space-bands rest, a pivoted cover having a depending rib adapted to lie within the 110 openings in the upper ends of the space-bands, spring-pawl and connections for raising one space-band at a time out of the box, and a stop carried by the cover and arranged to prevent more than one space-band at a time being discharged.

12. The guide or way for conducting the space-bands from the distributing-box to the space-band magazine provided with a pivoted entrance-plate.

13. In a linotype-machine, the combination with the assembling-box and the elevator, of a guide extending between said box and elevator, and the yielding resistant adapted to slide on said guide in advance of an assembled matrix-line during its passage from the assembling-box to and into the elevator.

14. In a linotype-machine, the combination with the assembling-box and the elevator, of the guide extending from said box to said elevator, a yielding resistant traveling with said guide, means for drawing said resistant constantly in the direction of the assembling-box, said resistant being adapted to travel with

the assembled line to the elevator, and means for lowering the elevator with the assembled line whereby the resistant is freed and permitted to return to operate upon a new line 5 in the assembling-box.

15. In a linotype-machine, the combination of the assembling-box and the yielding resistant therein, of a pawl or stop movable into the path of said resistant to limit the movement thereof and adjustable lengthwise of said path for different lengths of lines.

16. In a linotype-machine, the combination of the assembling-box, and the yielding resistant movable in said box in advance of the line 15 of matrices, with a pawl or stop for said resistant, said pawl or stop being capable of a lateral movement into and out of the path of the resistant.

17. In a linotype-machine, the combination 20 with the assembling-box and the yielding resistant movable therein in advance of a line of matrices, of a rock-shaft, a pawl or arm on said shaft adapted to swing into and out of the path of said resistant, a spring normally 25 tending to hold said pawl in said path, and a bevel on said pawl whereby the resistant in its reverse movement rocks the pawl out of its path.

18. The combination of the assembling-box 30 and yielding resistant, with a spring-actuated pawl normally held in position so as to act upon the resistant and to determine the length of the line and capable of being swung so as to release the resistant and the assembled line, 35 said pawl being provided with a bevel so as to permit the return of the resistant to its normal position.

19. In a linotype-machine, the combination 40 with the elevator, and means for temporarily holding the elevator in position to receive a line of matrices, of a mold, means for moving the elevator from the receiving position to the mold, a cam-shaft normally idle, and a starting device for the cam-shaft adapted to 45 be operated by the elevator as it moves from the receiving to the casting position.

20. In a linotype-machine, the combination 50 of a normally idle cam-shaft, a starting-clutch, a starting-lever, an elevator having a part adapted to operate said lever, means for holding the elevator temporarily in position to receive a line of matrices, and means for releasing the elevator, said elevator being arranged 55 to sink by its own weight from the receiving to the casting position and adapted to automatically operate the starting-lever as it approaches the latter position.

21. The combination of the assembling-box 60 and the elevator, with an adjustable stop upon which the elevator normally rests so as to be directly in line with the assembling-box.

22. The combination of the assembling-box 65 and the elevator, with the movable stop and with adjusting means between the elevator and the stop so that the elevator may be maintained in accurate alinement with the assembling-box.

23. The elevator provided with the retaining-pawl for holding the assembled line of matrices in position and means for adjusting 70 the pawl relatively to the elevator to adapt the elevator to different lengths of line.

24. The elevator adapted to move vertically and provided with adjustable means adapted to act upon the starting mechanism to start 75 the cam-shaft.

25. In a linotype-machine, the combination 80 of the main frame, the cam-shaft journaled in the rear portion thereof, the vise-cap arranged in the front part of the machine, and the bolts connecting said vise-cap with the rear portion of the frame, said vise-cap being adapted to sustain the elevator during the casting operation.

26. In a linotype-machine, the combination 85 with the main frame having rear standards in which the cam-shaft and cam-levers are mounted, the arch-shaped vise-cap in front of the machine, bolts connecting said vise-cap with the rear standards, the elevator, the mold, 90 and the melting-pot, said vise-cap being adapted to sustain the elevator while the mold and melting-pot are coöperating with the line of matrices during the casting operation.

27. The combination of the movable jaw, 95 a screw-threaded rod at the rear end thereof, and a spring, tending through suitable connections to turn said screw-threaded rod to lock the movable jaw in position, said spring movement being under the control of the justifying mechanism, with further means for giving said movable jaw an inward and yielding motion to close the mold for short lines and for returning it to its outward position.

28. In a linotype-machine, the mold-carrier 105 mounted upon a shaft capable of both rotary and longitudinal motion, and means for intermittently imparting rotary and longitudinal motion to the shaft, combined with an arm or bushing mounted on said shaft and pins 110 on the frame of the machine adapted to be engaged by said arm or bushing so as to firmly hold and lock the mold in its operative positions.

29. The combination of the mold-carrier, 115 the shaft on which said carrier is mounted, a gear also mounted on said shaft, means for imparting to said gear intermittent rotary motion, an arm or bushing also mounted on said shaft, and means for imparting an intermittent longitudinal motion to said shaft, with pins mounted upon the frame and with which the arm or bushing is adapted to engage so as to firmly lock the mold in its various operative positions.

30. In a linotype-machine, the ejector, combined with its supporting-frame, said frame being supported upon the mold-shaft and sliding upon rods of the main frame.

31. In a linotype-machine, in combination 130 with the mold and with the ejector, of suitable means for imparting to the ejector, first a partial ejecting movement, and finally a complete ejecting movement.

32. The combination with the pot, of the mold, the mold-shaft, and of the ejecting mechanism partially supported on said mold-shaft, the said parts being so placed above the pot as to permit of easy access to the ejector-blade.
33. In combination with the mold and ejector mechanism, of the means for trimming the base of the slug while it is still in the mold, of further means for trimming one of the forward edges of the slug while it is partially ejected from the mold, and of means for trimming the other front edge of the slug after it has been completely ejected from the mold.
34. In a linotype-machine, the combination with the mold, of a knife constructed and operated to trim one of the side faces of the slug while the latter is supported in and protruding from the mold.
35. In a linotype-machine, the combination with the movable mold, means for casting a slug therein, and means for ejecting the slug therefrom, of means for moving the mold from the casting to the ejecting position, a stationary knife adapted to trim the forward edge of the slug during said movement, a traveling knife arranged to trim one of the side faces of the slug as it is partly ejected from the mold, a stationary knife arranged to trim the other side face of the slug, and means for moving the slug past said knife after it is ejected from the mold.
36. In a linotype-machine, the combination of a mold and a trimming-knife arranged to move lengthwise of the mold and trim the side face of the slug while the latter is supported in and protruding from the mold.
37. In combination with the mold, of a knife impinging thereon, and of suitable operating mechanism for actuating said knife so as to trim one of the forward edges of the slug when partially ejected from the mold.
38. The knife box or block provided with spring-pressed surfaces for maintaining the slug in position and with a knife for trimming one of the forward edges of the slug, combined with suitable means for forcing the slug lengthwise through the knife box or block and past the trimming-knife.
39. The knife box or block, provided with a pressure-surface adapted to receive and hold the slug when it is ejected from the mold, in combination with a trimming-knife adapted to trim one of the forward edges of the slug, further pressure devices designed to firmly hold the slug in the box or block while it is being trimmed and means for moving the slug lengthwise through said knife-box.
40. The knife box or block, provided with pressure-surfaces and with a knife for trimming one edge of the slug, together with adjusting means for varying the knife box or block so that it may be adapted to slugs of different thicknesses.
41. In combination with the mold, and with ejecting mechanism, of a knife adapted to trim one edge of the slug when partially ejected from the mold, and a slug-shifter connected to said knife and adapted to force said slug through the knife-block for trimming the other edge of the slug, together with suitable actuating means for said knife and slug-shifter.
42. In combination with the elevator, and with a shifter for moving the assembled line from the elevator to the distributing mechanism and with a suitably-actuated arm for moving said shifter, of a pawl connected to the said shifter-arm and co-operating with a stud at the lower part of the frame, so that the shifter may be locked in inoperative position to permit the return of the elevator with the assembled line.
43. The main frame of the machine provided with a support, and keyboard, assembling and distributing mechanisms independently adjustable on said support.
44. The main frame of the machine provided with a vertical pillar or column adapted to receive collars on the keyboard, assembling, and distributing mechanisms, so as to permit of the independent adjustment of said mechanisms thereon.
45. The main driving mechanisms embracing a clutch, combined with suitable moving means therefor, and means whereby the actuation of the cam-shaft is initiated by the descent of the elevator.
46. The main driving mechanism embracing a clutch, and suitable mechanism connected thereto whereby the descent of the elevator initiates the actuation of the cam-shaft, combined with means connected to the cam-shaft whereby the clutch is disengaged after the required cycle of operations has been completed.
47. The main driving mechanism embracing a clutch for the actuation of the cam-shaft, combined with suitable means actuated by the descent of the elevator for initiating the operation of the cam-shaft, including a hand mechanism whereby the operation of the cam-shaft may be stopped and started at will.
48. The main driving mechanism embracing a clutch connected to the cam-shaft, which clutch is normally held out of engagement by starting means acted upon by a device carried by the cam-shaft, combined with suitable means whereby the descent of the elevator disengages the starting means from the device carried by the cam-shaft and permits the actuation of the cam-shaft until said starting means are again engaged by the said device.
49. The main driving mechanism, embracing a clutch connected to the cam-shaft, which clutch is normally held out of engagement by starting means acted upon by a device carried by the cam-shaft, and suitable means whereby the descent of the elevator disengages the starting means from the device carried by the cam-shaft and permits the actuation of the cam-shaft until said starting

means are again engaged by the said device, combined with a hand-operated device to permit the stopping and starting of the cam-shaft at will during its cycle of operations.

5 50. In a linotype-machine, a device adapted to drive all of the justifying-wedges simultaneously, in combination with a cam having an irregular contour adapted to advance the wedge-driving device with a jogging movement, for the purpose set forth.

10 51. In a linotype-machine, the combination with the justifying-lever, and a device connected thereto adapted to drive all of the jus-

tifying-wedges simultaneously, of a spring for operating said lever to drive the wedges, and 15 a cam for controlling the movement of said lever, said cam having an irregular face to impart a jogging or intermittent movement to said lever, for the purpose set forth.

In testimony whereof, I affix my signature 20 in presence of two witnesses.

OTT. MERGENTHALER.

Witnesses:

WILLIAM H. BERRY,
MURRAY HANSON.
